UNITED STATES PATENT OFFICE

108,963

DESIGN FOR AN AMUSEMENT GAME APPARATUS CABINET

Bruno Radtke, Libertyville, Ill., assignor to The Exhibit Supply Company, Chicago, Ill., a corporation of Illinois

Application February 3, 1938, Serial No. 74,847

Term of patent 3½ years

To all whom it may concern:

Be it known that I, Bruno Radtke, a citizen of the United States and a resident of Libertyville, in the county of Lake and State of Illinois, have invented a new, original, and ornamental Design for an Amusement Game Apparatus Cabinet, of which the following is a specification, reference being had to the accompanying drawing, forming a part thereof, and in which:

The single figure is a perspective view of an amusement game apparatus cabinet, showing my new design.

I claim:

The ornamental design for an amusement game apparatus cabinet, as shown.

BRUNO RADTKE.
